Nels Nelson,
Inventor
By Atty. Garret Symon

UNITED STATES PATENT OFFICE.

NELS NELSON, OF NEW HAVEN, CONNECTICUT.

DEVICE FOR PREVENTING FRAUDULENT REFILLING OF BOTTLES.

SPECIFICATION forming part of Letters Patent No. 613,465, dated November 1, 1898.

Application filed June 10, 1898. Serial No. 683,114. (No model.)

To all whom it may concern:

Be it known that I, NELS NELSON, of New Haven, in the county of New Haven and State of Connecticut, have invented a new Improvement 5 in Devices to Prevent the Fraudulent Refilling of Bottles; and I do hereby declare the following, when taken in connection with the accompanying drawings and the letters of reference marked thereon, to be a full, clear, 10 and exact description of the same, and which said drawings constitute part of this specification, and represent, in—

Figure 1, a side view of a device embodying my invention; Fig. 2, a vertical section thereof; Fig. 3, a sectional view on the line *a b* of Fig. 2; Fig. 4, a side view of the inner tube, collar, and yoke; Fig. 5, a sectional view on the line *c d* of Fig. 2; Fig. 6, a broken view illustrating the manner of supporting the locking-band; Fig. 7, a top view of the combined lock-case and locking-lever detached; Fig. 8, an inside view of the lock-case; Fig. 9, a transverse section through the lock-case and housing; Fig. 10, a side view of a key adapted to be used in connection with the lock; Fig. 11, a perspective view of one of the guide-clips for the bail-rods.

This invention relates to an improvement in devices to prevent the fraudulent refilling 30 of bottles, and particularly to that class which are attached to bottles of ordinary construction, from which they may be readily removed to permit the bottle to be filled, but from which they cannot be detached except by an 35 authorized person.

The object of the invention is to construct a device which, in addition to the complicated mechanism, requires that the bottle shall be turned into a certain position before the locking device can be released; and it consists in the construction as hereinafter described, and particularly recited in the claims.

The device consists of a cup-shaped cap *A*, adapted to set over the upper end of the neck 45 *B* of a bottle, which cap is formed with an upwardly-extending flange *a*, and its under edge rolled to form a reinforcing-rib *b*. Over the upper end of this cap and so as to extend downward into the neck of the bottle is placed 50 a tube *C*, formed at its lower end with fingers

c. At the lower end of this tube is a sleeve *D*, formed near its upper end with slots *c'* to receive the fingers *c*, whereby the sleeve and tube are coupled together. The upper end of this sleeve extends upward into the tube 55 and is contracted to form a valve-seat *E*. Below the sleeve is a yoke *F*, which is secured to said sleeve by striking tongues *d* outward from the face of the tube and bending them over the edges of the upper end of the yoke 60 *F*, which is formed with notches *f* to receive the said tongues. Extending through the yoke, tube, and sleeve is a pipe *G*, turned upward at its lower end and closed by a flap *H*, having an arm *H'*, which is pivotally connected with an eye *H''* on the pipe. Around the pipe is a tapered plug *I*, adapted to enter the seat *E* and so close the upper end of the sleeve *D*. Also around the pipe and above the plug is fixed a collar *J*, so that when 70 the plug is in its seat the collar *J* will rest upon the upper edge thereof and so as to support the pipe. Within the sleeve *D* is fixed a wire *e*, in the center of which is formed an eye, through which the pipe extends, and 75 fixed to the pipe between the eye and the lower end of the yoke *F* is a stop, which, as herein shown, consists of a coil of wire *g*, the upper end of which is adapted to strike the eye *e* and the lower end strike the yoke, 80 whereby the movement of the pipe *G* is limited. Over the upper end of the pipe is placed a fan-wheel *K*, so as to freely revolve thereon, and this is held in position by a fixed washer *L*. The cap *A* is held in position by a flexible band *M*, suspended from the lower edge of the said cap by loops *m*, *m'*, and *m''*, one only, as *m'*, being riveted to the band. To one end of the band is pivotally connected a lever *N*, which extends 90 through an eye *O*, fixed to the other end of the band and so that as the lever is turned the ends of the band will be drawn together. To the band is fixed a lock-case *P*, having a keyhole-shaped slot *p*, and in one end of this 95 case is mounted a counterbalanced lever *Q*, so that when held in one position the arms *q* of the lever will lie over upon the face of the case *P* and when reversed will move away therefrom. To the lever *N* is fixed a housing 100

R, in which is mounted a key-post S, having at its inner end an arm T, adapted to enter the case P through the slot p therein and be turned therein above the arms q of the lever 5 Q. Over the post is placed a washer r, and through the post, above the washer, is inserted a pin t, whereby the post is held in the housing. Over the post is placed a shell U, having ears u, which pass through slots in 10 the housing and so as to be turned down upon the inner face thereof, whereby the shell is held in position. The face of this shell is graduated in the usual manner of indicating-disks of combination-locks. The outer ends 15 of the key-posts may be of any irregular shape, and the keys V to be used therewith have a corresponding opening and are provided with a pointer V', which when the key is turned sweeps over the shell U and so as to indicate 20 the position of the locking-arm T. On each side of the band M is fixed a clip M', through which extend rods M², formed at their upper ends with eyes m³ and at their lower ends with heads m⁴, and on the rods, between the 25 heads and the clips, are spiral springs m⁵. Engaging with the eyes m³ is a bail W, supporting a stopper W', which is adapted to rest upon and close the upper end of the tube C, and preferably to this bail is fixed a loop 30 W², by which the bail may be raised so as to lift the stopper from the upper end of the tube C or place it thereon. This stopper is provided at its inner face with a rubber packing W³, as usual with bottle-stoppers. 35 The bottles are filled in the usual manner, and when full my improved device is placed in position and the lever N turned so as to clasp the band M around the neck of the bottle and so that the locking-lever passes into 40 engagement with the case P, the bottle being held in such position that the said arm will pass over the lever Q. When thus located, the contents may be removed by simply raising the bail so as to displace the stopper W', 45 and when the bottle is inverted the pipe G will slide, so as to allow the plug l to move toward the mouth of the bottle and permit the escape of the contents through the seat E and through the fan-wheel K, which by revolving will not obstruct the discharge-opening. In this inverted position the flap H will fall away from the end of the pipe, so that air will enter through it, and any of the 50 contents of the bottle which may pass outside of the sleeve will escape through the slots c'. When the bottle is held upright, the plug falls into its seat and the pipe drops down upon the upper end thereof and the fan-wheel prevents access to the plug. While 55 the bottle might possibly be filled through the vent-pipe, bottles could not be commercially so filled, and therefore this would constitute no objection to this class of bottle-stoppers. When the bottle is empty, the device can only be removed by one holding a 60 key having an opening corresponding to the

key-post S and knowing the relative position of the locking-arm, and so that when the key is applied and turned so that the indicating-finger points to a certain degree on the dial 70 the locking-arm T will pass off from the lever Q. When thus turned, the bottle must be held in a horizontal position, with the lock mechanism downward, and the key again turned until the locking-arm T is in line with 75 the slot p in the lock-case, so that the lever N is free to be turned to release the band. After the bottle has been filled or refilled the device is again attached, as before described. It will thus be seen that while the contents 80 of the bottle are readily removed the device cannot be detached, so as to permit the refilling of the bottle, except by one having a key with an opening corresponding to the shape of the key-post and knowing that it is 85 necessary to turn the bottle into a certain position to throw the lever out of engagement with the locking-arm of the key-post.

Having fully described my invention, what I claim as new, and desire to secure by Letters 90 Patent, is—

1. A device to prevent the fraudulent refilling of bottles, comprising a cap, a tube suspended from the upper edge thereof, a sleeve at the lower end of said tube, a seat in the 95 said sleeve, a pipe extending through said sleeve and tube, a plug on said pipe adapted to close said seat, a collar fixed to said pipe above said plug, a fan-wheel mounted at the upper end of said pipe for rotation thereon, a flexible band suspended from the edge of 100 said cap, and means for locking the ends of the said band together, substantially as described.

2. A device to prevent the fraudulent refilling of bottles, comprising a cap, a tube suspended from the upper edges thereof, a sleeve at the lower end of said tube, a seat in the 105 said sleeve, a pipe extending through said sleeve and tube, a plug on said pipe adapted to close said seat, a collar fixed to said tube above said plug, a fan-wheel mounted at the upper end of said pipe for rotation thereon, a flexible band suspended from the edge of 110 said cap, a lock-case fixed to said band and containing a counterbalanced guard-lever, a lever pivotally connected with one end of said band, and extending through an eye on the other end of said band, a housing fixed to said lever for engagement with said case, and a 115 locking-lever mounted in the said housing and adapted to engage with said counterbalanced lever, substantially as described.

3. A device to prevent the fraudulent refilling of bottles, comprising a cap, a tube suspended from the upper edge thereof, a sleeve at the lower end of said tube, a seat in the 120 said sleeve, a pipe extending through said sleeve and tube, a plug on said pipe adapted to close said seat, a washer fixed to said pipe 125 above said plug, a fan-wheel mounted at the upper end of said pipe for rotation there-

on, a flexible band suspended from the edge of said cap, means for locking the ends of said band together, vertically-movable rods mounted on opposite sides of said band, a bail connecting the upper ends of said rods and a stopper carried by said bail and adapted to close the upper end of said tube, substantially as described.

In testimony whereof I have signed this specification in the presence of two subscribing witnesses.
